4 Claims. (CL 1-2)

The improvement in the manufacture of sheet steel in the metal industry has recently reached an extremely high degree of perfection and thus sheet steel has been introduced into many branches of industry which hitherto were closed to it. Apart from the cheap manufacture of motor cars, another branch of industry which has been affected thereby is the construction of all-metal aircraft. The wall surfaces of metal car bodies and all-metal aircraft consist of overlapping metal sheets of considerable mechanical strength which have to be united in a permanent and reliable manner. Also the points at which they are united must be very close together so that the vibrations, which occur at high speed flight for example, are kept within the smallest possible limits.

Hitherto, such metal sheets have been united by means of rivets which are introduced into pre-formed holes and then up-set at both ends. A special automatic riveting machine has been developed which has a relatively high capacity but which has the drawbacks that it requires pre-formed holes 3-5 mm. in size to take the rivets which are then upset at both ends; moreover, this machine cannot be used everywhere due to its complicated construction and its size.

According to the present invention the principle of the wire stitching machine which is known for light work such as stitching paper and stapling boxes is made the basis of a machine for driving $\square$ -shaped cramps which is more strongly built to correspond to the new purpose and is adapted to exert a maximum driving force with the small stroke which is involved for the cramp-forming elements. In comparison with the purposes for which wire stitching machines have hitherto been employed the thicknesses of material to be stitched in accordance with the present invention are only small but very much stronger material is involved. This maximum driving force is obtained in that on the one hand the cams have an appreciably smaller throw corresponding to the smaller stroke so that with a constant power input a greater positive working pressure can be obtained, and on the other hand the time available for driving the cramps at the points where large generation of force is necessary can be made large at the cost of the time available for those movements which serve solely for guiding the cramps and which are small in comparison with the corresponding movements in the wire stitching machines hitherto employed for other purposes.

In comparison with the riveting machine which

has hitherto exclusively been used it is possible by employing the machine of the present invention to obtain not only many times the output but also a reduction of the cost to a fraction of the former amount. At the same time the stitched points exhibit greater strength than riveted points as regards continuous loading of the finished work. There is also the advantage that the new method of stitching can be used more readily than the more expensive riveting machine at points which are difficult of access.

By bending the shanks of the cramps outwardly greater strength is obtained than by bending the shanks inwardly, presumably because the bending outwardly causes the holes which are formed by the penetration of the cramp to be filled better than if there is the double bending in the same direction as when bending inwardly. The bending outwardly has in addition the very material advantage that the back of the cramp when being driven can be forced into the upper sheet metal layer so that the stitching point does not consist of two thicknesses of sheet metal plus two thicknesses of wire, but of two thicknesses of sheet metal plus one thickness of wire. In this way when utilizing the invention for aeroplane wings, for example, the air resistance is very considerably reduced and in other cases there is a neat appearance and small thickness. The material which is displaced projects beneath the back of the cramp into the free space between the outwardly bent shanks of the cramp. It is advantageous for the backs of the cramps to be made not more than 10 mm. long, as tests have shown that the load can then be increased appreciably.

Experiments have also shown that wire considerably thicker than that customary for stitching purposes in wire stitching machines in the book-binding industry can be employed. In this way the utility of the invention is further augmented and far exceeds that of the riveting machines hitherto exclusively employed for the same purpose. The shape of the wire employed is unimportant. It may be round, rectangular or square, and in spite of the highest strength of the work it is not necessary to employ wire of the same strength. Experiments have shown that iron wire penetrates harder material cleanly if it is driven with the requisite force, and during the driving period the cramp is entirely enclosed in its guides so that it cannot distort.

When securing metal plates together by the method and machine according to the present invention, the cramp—which may conveniently be

produced from a length of wire which is fed to the machine—itself constitutes a punch which makes the holes in the superimposed parts which are to be united. This punch however, is not withdrawn again but remains in the work, closes the holes completely and when the projecting ends of the shanks of the cramp are bent over at a sharp angle and firmly compressed, an ir-releasable connection is obtained.

The comparatively small cross section of the shanks of the cramp which act as punches suggests the possibility of the shanks being deflected from the precisely vertical direction when being forced through the work. However, with the arrangement as set out above in which the shanks are completely enclosed in guides above the work during the driving operation, this deflection does not occur to any appreciable extent. This makes it possible, according to another feature of the invention, to support the work on a matrix number, which forms a closely fitting guide on three sides for the projecting portion of each shank of the cramp which is driven through and projects from the work. The matrix member is provided with a slot for each shank, the slots being substantially of the same width as the shanks and of such a length as is necessary for the length of the shank of the cramp which has to be accommodated therein when it projects beneath the work before being bent over against the work. The slots terminate at a sharp edge in the surface of the matrix member so that the work is supported as close as possible to the points where the punch-like shanks of the cramps are driven through. The surfaces engaging the work from above and below are preferably concave and convex respectively, advantageously in the form of a spherical cap. These surfaces then tend to cause the work to become convex upwardly at the point where the cramp is driven, whereas the cramp driving operation tends to bend it in the opposite direction so that as a result a substantially straight surface is maintained.

One embodiment of a machine according to the invention is shown by way of example in Figs. 1 to 13 of the accompanying drawings in which:

Figure 1 is a front view of the machine,

Figures 2 and 3 show a section along the line II—II in the two extreme positions of the stitching mechanism,

Figure 4 is a section along the line IV—IV of Figure 1,

Figures 5 and 6 are sections along the lines V—V and VI—VI respectively of Figure 1,

Figures 7-11 show details,

Figure 12 is a side view of the entire machine and

Figure 13 shows the mechanism for adjusting for different thicknesses of work to be stitched.

The framework 1 (Figs. 2 and 12) carries at 2 the mechanism for forming and driving the wire cramps, this mechanism being driven from the shaft 3. The counter-member 5 is displaceably mounted and guided on the frame at 4. The member 5 is set to correspond with the thickness of the work which is to be stitched at any time and, as a very accurate setting over a small range is involved, a fine adjustment mechanism is provided. At the front, the head 2 of the frame 1 is constructed in the form of a housing and the driving shaft 3 extends into it. Mounted on the shaft 3 in the housing 2 is a crank 6, cam discs 8 and 9 and also a cam 10 on the cam disc 8 for moving the cramp forming parts. The

cam 8 effects the upward and downward movement of a member 7 which slides in the housing and which at the bottom carries interchangeable right and left-hand bending members 11 (Figs. 5-11) whereby the length of wire which forms the cramp and which is introduced horizontally as a straight piece of wire is bent into U-form over a block 12. On the inside these bending members 11 have grooves 13 in which are guided the shanks of the cramp, the grooves being completely closed by means of the cramp support 28 which slides between the limbs of the cramp. The driver 14 which drives the U-shaped cramp in front of it is also guided in the grooves 13 above the shanks of the cramp. This cramp support 28 is gradually expelled from beneath the cramp against spring action during the cramp driving operation but maintains the cramp channel constantly closed during that operation. Also guided in the member 7 is the driving plunger 15 (Figs. 7-11) which carries the driver 14. The crank strap 6' is secured to the plunger 15 which is guided in the housing 2 and when the cramp has been bent into U-shape it is carried downwardly by the driver 14 at the appropriate moment and driven through the work W (Figs. 2 and 3). The cam 9 serves for advancing a new length of wire. It actuates the lever 16 (Fig. 1) on which is mounted a gripper 17 which opens when the lever 16 swings to the left so as to slide freely over the wire but in the movement to the right it grips the wire and carries it along with it so that a definite length is introduced into the machine. The length of wire can be altered in known manner by adjusting the effective feed movement. The wire is introduced into the slot 26 in the bending block 12 (Fig. 2). In the example shown, the wire is introduced in the plane in which the cramp is driven and the stroke of the crank 6 is so large that there is sufficient time for the introduction of the wire. The cam 10 serves to sever the length of wire which has been advanced. It operates on a roller 18 which is carried on a member 19, which on the right-hand side carries the blade 20. A corresponding blade is carried on the housing 21 (Fig. 1).

Due to the downward movement of the roller 18, the wire is cut by means of these co-operating blades 20, 21. A spring 22 draws the member 19 upwardly again. In order to allow the cramp to be forced through the work slowly and effectively during that part of the plunger movement in which this operation is timed to occur, the corresponding point 23 of the crank strap 6' where the crank 6 engages it is shaped in the form of a cam (Fig. 1) so as to give a retardation of the movement and an increase in the driving force. If the crank 6 operates in a straight guide groove, it is clear that the resultant driving stroke will be a simple harmonic motion. The guide groove, however, is a cam groove which, broadly speaking, can be described as concave downwardly. The result is that in the first part of its movement from the top dead center position, the crank 6 will impart a more rapid driving movement than if the guide groove were a simple straight groove at right-angles to the driving direction. The more rapid movement will persist for about 90° rotation from top dead center. During the succeeding 90° rotation to bottom dead center, the downward concavity of the guide groove serves to reduce the driving movement, and if the radius of the concavity were equal to the crank radius, the driving movement would be reduced to zero. By suitable

choice of the two radii, any desired slow driving movement can be produced during this phase of the rotation of the crank 6. As a constant driving torque is applied to the shaft 3, it follows that the pressure generated by the crank 6 can be much greater during the slow phase of the movement of the driver than during the rapid phase. Instead of this mechanism any other arrangement of any suitable kind could be provided whereby at the moment the wire cramp encounters the work and during the period of its penetration a special pressure is exerted on the plunger 15 carrying the driver, thereby relieving the load on the crank 6 and its strap 6' or else making them entirely unnecessary. This could be effected, for example, by straightening a toggle by means of a separate drive, a differential gearing or the like.

The bending of the wire to form the cramp and the guidance of its shanks are effected in the following way:

Firmly mounted on the frame so as to be rotatable about 24 is the bending block 12, which by means of the spring 25 is constantly urged inwardly on the stitching head (i. e. to the left in Fig. 2) so that when the wire is introduced it enters the slot 26. On the other side the cramp support 28 is mounted at 27 on the member 7 which moves up and down. The cramp support 28 carries a roller 29 which encounters a cam 39 which is so shaped that during the downward movement of the bending members 11 the cramp support 28 cannot swing forwardly under the action of the spring 31. Thus the bending members 11 engage the length of wire which is beneath them and bend it downwardly on the right and the left of the bending block 12 so as to bend it into U-shape. On further movement in the downward direction in which the support 28 participates, the point 28' of the support 28 passes between the shanks of the cramp so that when subsequently the driver engages the back of the cramp and thereby expels the bending block 12 to the right (Fig. 3), the cramp is completely enclosed in the channels in the bending members and after encountering the work cannot buckle under the pressure which constantly increases up to the moment of penetration; consequently the cramp must pass through the material. Experiments have shown that iron wire of 1 mm. cross section is capable of penetrating sheet steel of about 2 mm. thickness if the machine and the elements which have to generate and transmit the effective pressure are made correspondingly strong.

The mechanism for clinching the ends of the cramp can either consist of a rigid block provided with depressions which during the stitching operation bend the cramp shanks inwardly or outwardly or may consist of movable elements which engage the cramp shanks after the cramp has been driven completely through the work, bend them outwardly and urge them upwardly against the work. This mechanism also must be so strong that there is no yielding so that the wire lies close against the work. When the shanks of the cramp are bent outwardly the material beneath the back of the cramp can be forced into the cavity between the two bent ends of the wire by exercising a correspondingly heavy pressure from above, so that at the point of stitching the upper side is flush with the surface of the work.

An example of the first-mentioned type of clinching mechanism is indicated in Fig. 1 where

5 a rigid block 32 is provided. As the shanks of the cramp pass through the work they are progressively bent over against the underside of the work. With this arrangement it is advantageous to subject the points of stitching to a subsequent pressing operation in a press in order to make the back of the cramp flush with the surface. The adjustment to the thickness of the work which is to be stitched is effected by means of a handwheel 33 (Fig. 13) on the shaft 34, on which is mounted a worm 35 which engages in the worm wheel 36. This rotates the eccentric pin 37 which moves the plunger 38 on which the table 39 is carried. The table 39 is locked in the adjusted position by means of the locking handle 40 which can be clamped in an arcuate slot in a lever 41 fast on the same shaft 42 as the worm wheel 36.

10 The clutch of the machine is so arranged that the machine is always brought to rest when the stitching mechanism is raised (Fig. 2) so that the work can conveniently be positioned beneath it.

15 An example of the second type of clinching mechanism which constitutes a further feature of the present invention is shown in Figs. 14 to 22 of the accompanying drawings, in which:

20 Fig. 14 shows a front view of a wire stitching machine provided with the clinching mechanism,

25 Figures 16 to 22 are detail views, in which Figure 16 shows U-shaped cramp on engaging the work,

30 Figure 17 is a section along the line XVII—XVII of Fig. 16,

35 Figure 18 shows the cramp after the work has been penetrated,

40 Figure 19 is a section along the line XIX—XIX of Fig. 18,

45 Figure 20 shows the ends of the cramp bent over,

50 Figure 21 is a section along the line XXI—XXI of Fig. 20,

55 Figure 22 shows the finished work.

55 In so far as parts are shown in Figs. 14 to 22 corresponding to those already described in Figs. 1 to 13, the same reference numerals are employed and the parts are not further described.

60 The wire feeding and cramp forming and driving mechanisms are the same as those previously described except that the appropriate length of wire 4 is fed in by rollers 47' instead of by the oscillating gripper 17. The adjustment for different thicknesses of work to be stitched is also the same as that already described.

65 The clinching mechanism of Figures 14 to 21 operates on a different principle from that previously described with reference to Figures 1 to 13 and will now be described. During the time the shanks of the cramp are being driven through the work by the action of the stitcher head, the work is supported from below by a counter-member 110 which is in the form of a matrix provided with slots 111 to receive the shanks without deflection. These slots are of substantially the same width as the shanks of the cramp and are so arranged that they embrace the shanks closely on three sides. On the fourth side, corresponding to the length of the slot, room is left for the subsequent bending over or clinching of the shanks. The slots 111 terminate at sharp edges in the surface of the member 110 so that on three sides the work is supported as close as possible to the point of penetration of the shanks so that a more or less complete punching action

is obtained which prevents a breaking away or distortion of the work at the points at which the clamp shanks pass through it. The length of the slots 111 should also be as small as possible so that the bending of the work where it is subjected to the punching pressure is reduced to a minimum. Plungers 112, 113 are moved up and down in these two narrow slots 111. The plungers each terminate in a dished depression in which during the upward movement of the plungers the shanks of the clamp are rolled inwardly or outwardly and finally are urged firmly against the work.

The plungers 112, 113 are secured on a rod 114 which at its lower end is connected to one arm of a bell crank lever 122, to the other arm of which an internally threaded sleeve 124 is detachably secured by a pivot pin 121. The sleeve 124 is threadedly engaged with a rod 123 which is moved to and fro by means of a cam mounted on a driven shaft of the machine. In this way the clinching plungers 112, 113 are actuated at the appropriate moment. By releasing the pin 121, the sleeve 124 can be rotated relatively to the rod 123 for adjustment purposes.

In the foregoing and in the accompanying drawings the invention has been set forth with reference to an arrangement for automatic clamp formation from wire fed to the machine, but it will be apparent that a machine according to the invention could be adapted to operate with pre-formed clamps which are introduced into a magazine provided on the machine.

I claim:

1. A machine for uniting overlapping layers by driving U -shaped wire clamps therethrough and clinching the shanks of the clamps on the other side of the work, comprising a work support, said support having two slots therein, one for each shank of the clamp, of substantially the same width as the clamp shanks to permit the unobstructed emergence of said shanks while supporting the work as close as possible to the points of emergence of the shanks, said slots extending in the direction of the back of the clamp and outwardly from the points of penetration of the shanks, dished plungers movable in said slots to clinch the shanks outwardly, and positive cam-operated means for moving said plungers to perform said clinching operation after the clamp has been driven through the work to its full extent.

2. A machine for uniting by means of wire clamps overlapping plates of small thickness but considerable resistance to the penetration of the clamps, comprising plate supporting means on one side of the plates, a clamp receiving guide on the other side of the plates and a driving mechanism for driving the clamp through the plates, means for actuating the clamp receiving guide and the supporting means to grip the work before the clamp driving operation, the supporting means having an upper convex surface and the guide having spaced material engaging por-

tions so as to impart to the staple-entering side of the work a convex curvature opposite to that which the clamp driving operation tends to impart to the work.

3. A wire-stapling machine comprising a support for sheet metal material to be stapled, a staple-receiving guide having walls engaging the outer three sides of each shank of the staple, a wedge-shaped member having its parallel sides in engagement with the inner sides of the shanks of the staple and cooperating with the walls of the guide to completely enclose all sides of the shanks of the staple, said wedge-shaped member having its inclined-sides lying between the bridge of the staple and the material to be stapled, means for pressing the lower ends of the guide against the material to be stapled and the shanks of the staple through the material to be stapled, means operable in synchronism with the pressing means for retracting the wedge-shaped member from the staple as it is pressed into the material, said support having two slots formed therein of a width substantially equal to the thickness of the staple shanks, of a length substantially equal to the length of the shank ends projected through the material to be stapled, and spaced apart a distance substantially equal to the distance between the shanks of the staple whereby the shanks will be engaged by three walls of said slots, and means reciprocably mounted in said slots for bending the ends of the shanks extending down into the slots outwardly and back against the material to be stapled.

4. A wire-stapling machine comprising a support for material to be stapled, a staple-receiving guide having walls engaging the outer three sides of each shank of the staple, a wedge-shaped member having its parallel sides in engagement with the inner sides of the shanks of the staple and cooperating with the walls of the guide to completely enclose all sides of the shanks of the staple, said wedge-shaped member having its inclined sides lying between the bridge of the staple and the material to be stapled, means for pressing the lower ends of the guide against the material to be stapled and the shanks of the staple through the material to be stapled, and means operable in synchronism with the pressing means for retracting the wedge-shaped member from the staple as it is pressed into the material, said support having two slots formed therein of a width substantially equal to the thickness of the staple shanks, of a length substantially equal to the length of the shank ends projected through the material to be stapled, and spaced apart a distance substantially equal to the distance between the shanks of the staple whereby the shanks will be engaged by three walls of said slots, the upper surface of the support being convex and the lower ends of the staple guide being spaced apart to impart a convex configuration to the upper staple-entering surface of the material to be stapled.

OSKAR KLEINSCHMIT.
